UNITED STATES PATENT OFFICE

157,538

CIGARETTE DISPENSER OR THE LIKE

Louis Rossi, Bronx, N. Y.

Application June 11, 1949, Serial No. 3,208

Term of patent 14 years

(CL. D85—2)

To all whom it may concern:

Be it known that I, Louis Rossi, a citizen of the United States of America, and a resident of Bronx, county of Bronx, and State of New York, have invented the new, original, and ornamental Design for a Cigarette Dispenser or the like, of which the following is a specification, reference being had to the accompanying drawing, forming part thereof, in which:

Fig. 1 is a perspective view looking at the front of the device;

Fig. 2 is a side elevation;

Fig. 3 is a front elevation; and,

Fig. 4 is a rear elevation thereof.

I claim:

The ornamental design for a cigarette dispenser or the like, as shown.

LOUIS ROSSI.
